MANIFOLD CONNECTION LOCK

Filed Nov. 10, 1921

FIG. 1.

FIG. 2.

Inventor

L. B. Martin,
By A. Patterson

Attorney

UNITED STATES PATENT OFFICE.

LESTER BRYAN MARTIN, OF FORD, VIRGINIA.

MANIFOLD CONNECTION LOCK.

Application filed November 10, 1921. Serial No. 514,280.

To all whom it may concern:

- Be it known that I, LESTER BRYAN MARTIN, a citizen of the United States, residing at Ford, in the county of Dinwiddie and State of Virginia, have invented certain new and useful Improvements in Manifold Connection Locks, of which the following is a specification, reference being had therein to the accompanying drawing.
- This invention relates to improvements in manifold connection locks, and more particularly to a device adapted to be sold as an appliance which will be applicable to any and all Ford automobiles now on the market for locking and holding the nut which makes the connection between the exhaust manifold of the automobile engine and the exhaust pipe which leads to the muffler.
- The primary object of my improved invention is to provide a lock for the manifold connection nut on a car of the Ford type, which will insure that the connection between the manifold and exhaust pipes of the engine will be held firmly, so that there will be no leakage or blowing through of the exhaust gases at the pipe connection and that the connection cannot become loose and broken entirely.
- A further object of my invention is to provide an attachment of the nature described, which can be quickly and easily attached to and detached from the automobile engine exhaust manifold connection.
- Another object of my improved invention is to provide a device of the character described which is cheap and simple to manufacture.
- A still further object of my improved invention is to provide a device of the character described, which is efficient in operation.

In the drawings:

Figure 1 is a side view of the rear end of a Ford automobile engine, showing the exhaust system of the engine, having applied thereto my invention.

Fig. 2 is a perspective view showing in detail the component parts of my invention.

Referring now to the drawings, in which like parts are designated by similar reference numerals throughout the entire description, A represents what I have termed the nut clamp and is preferably made from a flat piece of metal bent to form a hollow hexagonal shape, as clearly appears in the

drawing. B represents what I have termed a retaining member and is likewise preferably made of a flat piece of metal.

Referring now in more detail to the drawings, and particularly to Fig. 1 thereof, it will clearly appear that 1 represents the cylinder head of a gasoline motor of the Ford type. In motors of this type the head is detachable, being held in place by suitable bolts 2. The exhaust manifold of the motor is designated by the numeral 3, and the exhaust pipe by the numeral 4. The exhaust manifold of the engine is held in place by cross-arms 14, which bear against the downwardly projecting portions 15, of the manifold and are held in place on the bolts 16, by suitable nuts 17. The exhaust pipe has one end connected to a muffler (not shown) while its other end is connected to the exhaust manifold 3, by a hexagonal-shaped nut 5. The transmission housing of the machine appears at 6 and is provided as is common with a removable cover 7, held in place by suitable bolts 8. The main motor block is 80 designated at 9 and is provided with a removable plate 10 to permit access to the valve stems of the motor, and is held in place by a suitable bolt 11. The dash-board of the car is shown at 12 and the foot-board 85 at 13.

From experience I have found that due to the jars to the machine while running over rough roads and the vibration caused by the running of the engine that the hexagonal nut 5, which connects the exhaust pipe 4 to the exhaust manifold 3 of the engine, works loose and allows the exhaust gases to blow through the pipe connection and, in some cases, the nut works entirely loose allowing the pipe connection to be entirely broken. To overcome and cope with this condition, I have designed a simple and effective lock for locking the hexagonal nut 5, after the same has been tightened to make the connection between the exhaust pipe 4 and the manifold 3 of the engine.

This lock consists, as above mentioned, of the nut clamp A and the retaining member B. The nut clamp A comprises a flat piece of material bent to form a hollow hexagonal shape having a plurality of flat sides 19. At one of its sides, designated at 20, the ends of the material from which the clamp is constructed, meet and are bent outwardly at right angles to the side 20 of the

clamp A in separated parallel relation to form ears 21 and 22. The clamp A is then placed about the hexagonal nut 5 which has been previously tightened to make the connection between the exhaust pipe and the manifold of the engine. The retaining member B, which consists of a flat piece of material, is provided at one end with the slot opening 23, while adjacent its other end 10 it is twisted as at 24 to make its other end 25 lie in a plane at right angles to the main portion 26 of the retaining member.

A screw headed bolt 27 is then inserted through suitable openings in the ears 21 15 and 22 of the nut clamp A. The end 25 of the retaining member B is provided with an opening to receive the screw-threaded bolt 27, and this opening is placed over the bolt and the clamp and the retaining member are 20 then clamped in position by means of the nut 28 carried on the outer end of the bolt 27. After the parts have been clamped by means of the nut 28, the extreme end 29 of the retaining member B is bent outwardly at right 25 angles, as shown, thus holding the nut 28 locked against rotation and preventing the same from becoming loosened. The opposite end of the retaining member B, which carries the slot 23 now rests in a position over 30 the bolt 16, which carries the cross-arm 14 for retaining the exhaust manifold 3 in place. Due to the design of the retaining member B, as to its length and the bend or twist 24, it will be found that the slot 23 will 35 be so positioned as to go down upon the bolt 16 on all Ford machines. After placing the slot 23 of the retaining member B on the bolt 16, the nut 17 is tightened down upon the member.

40 From the foregoing it will be seen that I have provided an absolute lock for the manifold exhaust connection and that this lock is easily and readily attached and detached. The nut clamp A cannot move upon the hexagonal nut 5, due to the fact that it is tightly 45 clamped about the nut by means of the bolt 27 and the nut 28. The retaining member B is firmly connected to the nut clamp A by means of the bolt 27 and the nut 28 and the 50 retaining member in turn locks the nut 28 against loosening. Any possible movement of the hexagonal connection nut 5 is guarded against by the retaining member B, which is rigidly held upon the bolt 16 by means of 55 the nut 17. Once the nut 5 is tightened and my device is applied, as described, there is no way in which the manifold and exhaust pipe connection can become loosened or broken.

60 Although in the drawings and throughout the description I have shown and described the retaining member as being attached and held to the bolt 16, I wish it to be readily understood that the retaining member could 65 be made of a shape and size to have its end

carrying the slot 23 fastened to the bolt 8 in the removable cover on the transmission housing; one of the bolts 2 holding the cylinder head in place; or the bolt 11, which holds the removable plate 10 against the 70 main motor block 9, without departing from the spirit of my invention. The manner of fastening the end of the retaining member, shown in the drawing, is the desired manner, as I have found it to be easier to attach 75 the device in this way than to the other bolts above spoken of.

It is my desire and intention to cover by the claims of this application and to protect my invention whether the same is constructed 80 to be attached as shown in the drawings, or attached in one of the several manners above spoken of.

I desire further to point out that because of the slot 23 in the end of the retaining member for engaging the bolt 16, my device can be applied to any Ford engine now on the market. This slot gives leeway for an increase or decrease in the distance from the hexagonal nut 5 to the bolt 16 of the 85 exhaust manifold, which distance is slightly different in different model engines. 90

Having thus described my invention, what I claim and desire to secure by Letters Patent is:

1. A nut lock, of a hollow hexagonal shape provided with outwardly extending parallel ears, a bolt extending through the ears for compressing the hexagonal clamp, a retaining member having a portion of its length bent in a plane at right angles to its other portion, one of the portions of the retaining member greater in length than the other and provided with an opening, the other portion of the retaining member provided with an opening and an extending end adapted to be bent outwardly at right angles, this end of the member being clamped beneath the nut carried by the clamping member bolt, and the outwardly extending end of the retaining member bent outwardly to lock the clamping nut against rotation. 105

2. A nut lock comprising a clamping member adapted to be clamped about a nut 110 by means of a compression member, a retaining member for locking the clamping member against rotation, the retaining member having one end attached to the clamp by means of the compression member and its opposite end adapted for connection to an anchor. 120

3. A nut lock comprising a clamping member adapted to be clamped about a nut, a retaining member carried by the clamping member, and the retaining member having a portion of its length bent in a plane at right angles to itself, for the purpose described. 125

4. A nut lock comprising a clamping 130

member provided with outstanding parallel ears, a bolt carried by the ears for compressing the clamping member about a nut, a retaining member having one end fastened beneath the clamping member bolt and its end bent to lock the bolt against rotation, and the opposite end of the retaining member adapted to be fastened to an anchor.

5. A nut lock comprising a clamping member, provided with a bolt to compress the same, a retaining member carried by the bolt and adapted to be fastened to an anchor, and one portion of the retaining member bent in a plane at right angles to

its other portion for the purpose described. 15

6. A nut lock comprising a clamping member provided with a bolt for compressing the same, a retaining member having one end fastened beneath the bolt and its other end provided with a slot, a portion 20 of the retaining member bent in a plane at right angles to its other portion, and the slotted end of the retaining member fastened to an anchor, for the purpose described. 25

In testimony whereof I hereunto affix my signature.

LESTER BRYAN MARTIN.
